METHOD OF PRODUCING NEEDLED FELTS
Marshall McKew, Schodack Center, and Francis L. McKone, Albany, N.Y., assignors to Huyck Corporation, Stamford, Conn., a corporation of New York
Filed Jan. 11, 1963, Ser. No. 250,806
7 Claims. (Cl. 28—72.2)

This invention relates to a novel felt construction for use in a paper making machine and to methods of and apparatus for producing the same. The highly improved felt is produced by needling a batt of fibers to a base fabric under conditions insuring high tensile strength of the felt in both the machine direction and the cross machine direction. For this purpose it has been found highly important to provide a special relationship between the barbs of the felting needles and the directions in which the warps and wefts of the base fabric extend and the general direction in which the longitudinal axis of the fibers of the batt extend.

Heretofore, in needling a batt of fibers to a base fabric, for the production of a paper making felt, the importance of maintaining the special relationship between the directions in which the barbs of the needles, the warps and wefts of the base fabric, and the fibers of the batt extend, as contemplated by the present invention, has not been appreciated. In the conventional practice of needling a fiber batt to a base fabric, the felting needles have usually been provided with barbs extending in three or more directions from the axis of each needle used in a needling machine. Even when needles have been used that have barbs pointing in one or two directions, there has no appreciation of the need for aligning the needles so as to point all of the barbs in certain specific directions. Thus, no particular attention has been paid to the directions in which the barbs of one needle, of the multiplicity of needles used in a needling machine, extend in relation to the barbs of other needles of the group. Furthermore, in those instances in which some effort may have been made to direct the barbs of the various needles in some definite relationship to each other, the barbs of the various needles have not been pointed in the direction or directions found to be essential, for the purposes of the present invention, in relation to the warps and wefts of the base fabric, and no attention has been paid to the relationship between the direction in which the bars extend and the general direction in which the fibers of the batt extend or are oriented.

In accordance with the preferred embodiments of the present invention the barbs provided on each needle extend in only one direction, or at most two directions, from the longitudinal axis of the needle. Thus a needle having a triangular cross-section in the barbed region thereof will have the barbs extending outwardly from the axis of the needle at only one corner or edge of the triangular configuration, or will have the barbs similarly extending outwardly from two corners or edges of the triangular configuration. When such needles are used in a needling machine, care is exercised to have all of the barbs on the multiplicity of needles extend in substantially the same direction or the same two directions.

Also, according to the present invention, the direction in which the barbs extend from the needles should bear a quite definite relationship to the direction in which the warps, the wefts or filling yarns, and the longitudinal axes of the batt fibers extend. When the needle is of such character that its barbs extend only in one direction, this should be parallel to the warps and perpendicular to the wefts and to the general or major direction in which the batt fibers extend. It will be appreciated that the batt fibers are not strictly linear but have a wavy configuration. Therefore, orientation of the fibers will be understood as referring to the general longitudinal axis of the fibers. Also it will be appreciated that in the carding

2

of fibers it is not possible or practicable to align their axes 100% in the desired direction. However, in accordance with the present invention it is highly desirable to align the axes of the fibers to the extent of at least 70% in the specified direction. If the needles employed have barbs extending in two directions, these should preferably be at an angle of at least 120° to each other and they should preferably be pointed at not more than 30° to the direction in which the warps extend, and preferably at least 60° to the direction in which the wefts and the general longitudinal axes of the batt fibers extend. It will be appreciated, however, that the benefits of the invention may be achieved to a substantial extent if the angular-relationships specified are varied slightly. Thus if the bars are so disposed as to point in a direction of as much as 35° to the warp direction and as little as 55° to the weft or filling direction, substantial benefits will be derived over the results obtained when some or all of the barbs are pointed at an angle of 45° or more to the direction of the warps. In the case of needles having a barbed section of triangular cross-section, as described above, the barbed portion of the needle preferably forms an equilateral triangle in cross-section.

In speaking of "warps," it should be understood that this is meant to refer to the machine direction of the belt that is formed, regardless of whether they are the true warps or the filling yarns that are incorporated into the fabric in the loom. Therefore, whenever "warp direction" is mentioned herein this should be considered as meaning machine direction and whenever weft or filling direction is mentioned this should be understood as meaning cross machine direction.

While it has been found highly desirable to provide the needles with a triangular cross-section in the barbed portion of the needle, this portion of the needle may have a variety of other configurations, such as circular, oval, diamond-shaped or the like, so long as the barbs provided are adapted to be directed either parallel with the warps of the base fabric or at an angle of not more than 35° and preferably not more than 30° to the direction of the warps of the base fabric.

In some instances it is possible to provide each needle with barbs extending in more than two directions from the axis of the needle. Thus in the case of a needle having a barbed portion of hexagonal cross-section it is permissible to have the barbs extending outwardly from four of the corners; but these should be so arranged that when the needles are attached to the reciprocating head of the needling machine, all of the barbs will preferably extend at angles of 30° to the warp direction and at 60° to the filling or weft direction, and also the direction of orientation of the batt fibers. Similarly, if the barbed portions of the needles are of octagonal cross-section, the barbs may extend outwardly from four of the corners that are so disposed, when the needles are mounted in the reciprocating head of the needling machine, that the barbs will point in directions of 22.5° to the direction of the warps and in directions of 67.5° to the direction of the wefts and the direction of orientation of the batt fibers.

By performing the needling operation in accordance with the present invention, the resulting felt has a high tensile strength in the machine direction, and also a higher than usual tensile strength in the cross machine direction. The preservation of tensile strength in the machine direction results from the minimum damage done to the warp threads, by virtue of having the needle barbs extend in a direction parallel with, or at an angle of preferably not more than 30° to the warps. Improved tensile strength in the cross machine direction results from the fact that any cutting or nicking of the wefts or filling yarns is more than offset by the batt fibers which are firmly secured

to the wefts and extend in the weft direction to add to the tensile strength in that direction. In this connection it should be noted that any tendency of the needle barbs to cut into, and partially sever, the wefts or filling yarns is minimized by the pick up of batt fibers by the barbs before the latter pass through the normal path of the wefts. This tends to deflect the wefts or filling yarns sufficiently to avoid serious cutting. Moreover, whenever cutting or nicking of the wefts does take place, the fibers of the batt which are then firmly retained by the wefts and bridge the cuts or nicks formed in the latter, serve to supplant the tensile strength lost through the partial severance of the wefts. Moreover, the present invention reduces fiber shedding to a minimum. This is a highly desirable characteristic of the resulting felt.

With the foregoing objects and purposes in view the invention will now be described in further detail in reference to the accompanying drawings, in which:

FIG. 1 is a diagrammatic view, showing on an enlarged scale, the construction of the base fabric and the relative position of a number of barbed needles in applying the fibers of the batt thereto;

FIG. 2 is a schematic view, as a cross-section through the base fabric and a layer of batt fibers thereon in a direction parallel with the weft or filling yarns, and shows two of the barbed needles in their lowermost position;

FIG. 3 is a schematic view, similar to FIG. 2, but showing a cross-section through the base fabric and batt fibers in a direction at right angles to that shown in FIG. 2;

FIG. 4 is a greatly enlarged cross-sectional view through the barbed portion of one form of needle that may be used, the cross-section being taken at different levels to show the barbs which are located at different elevations along the needle;

FIG. 5 is an enlarged elevational view of a typical needle that may be employed in accordance with the invention;

FIG. 6 is an enlarged cross-sectional view through the barbed portion of the needle, taken along the line 6—6 of FIG. 5;

FIG. 7 is a view similar to FIG. 6, but taken along the line 7—7 of FIG. 5;

FIGS. 8 and 9 are views similar to FIGS. 6 and 7, respectively, but showing needles having a circular cross-section in the barbed region;

FIGS. 10 and 11 are cross-sectional views, taken at different elevations through needles having barbed portions of oval and diamond-shaped cross-section, respectively;

FIG. 12 is a diagrammatic view illustrating the relationship between a carding machine and a lapping machine employed for the production of a multi-layered batt having its fibers all extending in substantially the same direction; and

FIG. 13 is a schematic view of a needling machine that may be employed in accordance with the invention.

It will be understood that the base fabric, schematically shown in FIG. 1, may be produced of any desired width and length from yarns of any suitable character. They may be formed of wool, or of any other fibers conventionally employed in the production of paper machine felts. If the fabric is woven flat, the warps in the loom will be positioned in the machine direction of the felt to be produced therefrom, while the wefts or filling yarns in the loom will be positioned in the cross machine direction. On the other hand, if the fabric is woven in endless fashion the loom warps will extend in the cross machine direction and the loom wefts in the machine direction of the belt-like felt being produced. For the purposes of the further discussion of the invention, the term "warp" shall be understood as indicating the yarns which extend in the machine direction and the term "weft" or "filling" shall be understood as referring to the yarns extending in the cross machine direction.

While the base fabric may be of any of a variety of different weaves, the form shown in FIGS. 1, 2 and 3 is of such a character that the warps 10 pass over a single weft or filling yarn 11 and then under the next three filling yarns, with this pattern being repeated throughout the length of the fabric. Similarly the wefts pass under one warp and then over three warps in a repetitive manner across the width of the fabric. This serves to position the major portion of the wefts at the top surface of the fabric and the major portion of the warps at the bottom surface of the fabric. As the fabric is being advanced in the machine direction through a needling machine of any of a variety of conventional forms, a batt 12 formed of multi-layers of fibers, largely oriented substantially in the direction of the filling yarns, is applied to the upper face of the fabric. In the region of the needling machine in which a reciprocating head, or a plurality of such heads, is provided a large number of needles 13 is forced downwardly through the batt and through the base fabric. The barbs of the needles will carry portions of groups of fibers downwardly and will leave them in substantially U-shaped loop form, as indicated at 12a in FIG. 2, to present parallel leg portions in planes perpendicular to the directions in which the barbs extend from the axes of the needles, or parallel with the direction of orientation of the fibers. It will be appreciated that in the actual final product the loops of fibers so produced will have their legs much closer together and more nearly parallel than is shown in the enlarged schematic view of FIG. 2. It will be understood that the needles 13 are provided in a plurality of rows which extend completely across the width of the material to be needled. In plan, the arrangement of the needles in relation to the warp and filling yarns of the base fabric may be as schematically indicated in FIG. 1. The reciprocating head or heads carrying the needles will be reciprocated at a suitable speed through a distance of say 3 inches, to carry the pointed ends of the needles downwardly through the batt and the base fabric, from a point above the batt to a point about $\frac{1}{2}$ inch below the base fabric.

In FIGS. 1, 2 and 3 the needles are shown as having their barbed portions of triangular cross-section, with the barbs 13a of all needles pointing in a direction parallel with the warps 10 and perpendicular to the wefts or filling yarns 11. These barbs are also pointed in a direction substantially perpendicular to the lengthwise orientation of the fibers of the batt. The barbs provided in the needles may be of a variety of different forms, but it has been found desirable to make them of the so-called A type. This, as best shown in FIG. 3, makes it possible for a barb to receive a plurality of batt fibers without danger of having the fibers wedged into the upper end of the barb opening. Thus, when the needles are moved upwardly the batt fibers will tend to remain in the positions to which they have been forced by the downward movement of the needles. The fibers of the batt will not become wedged in the barb openings of the needles.

In some instances, certain of the needles will be found to carry their barbs into direct engagement with the filling yarns, with some resultant nicking of these yarns, as indicated for one of the needles shown in FIG. 3. However the fact that the barbs, at the time of their engagement with the filling yarns, carry a number of batt fibers downwardly within the barb opening tends to minimize the extent of cutting or nicking of the filling yarns, and also tends to leave the batt fibers, so carried, in a position within the filling yarns and firmly attached thereto. This tends to minimize any weakening of the cross machine direction strength of the finished felt structure. In fact, the orientation of the batt fibers in the cross machine direction builds up a certain amount of strength in that direction.

It will be understood that in the course of operation of the needling machine, the base fabric and the batt will

be continuously advanced in the direction of the warps, and this movement of the material preferably is such as to carry the wefts and the batt fibers toward the barbs of the needles. While this increases the tendency of the barbs on the sides of the needles that are opposite the direction of motion to cut into or nick the filling yarns, it has been found to improve the bonding of the batt fibers to the base fabric in the course of the needling operation. The net result appears to be an improvement of the end product produced, as compared with one formed by having the barbs of the needles pointed in the opposite direction, i. e., in the direction in which the base fabric and batt are being advanced. However, quite satisfactory results are obtained if this reverse arrangement of the barbs is employed.

In order to insure the desired extent of needling of the batt fibers into the base fabric, it is preferable to cycle the material through the needling zone a number of times. The number of passes required to bring about the desired attachment of the batt to the base fabric will depend, in fact, upon the depth of penetration and density of needling, i.e. penetrations per square area, the latter being governed by the relative speeds of the reciprocating head of the needling machine and the advance of the work.

In some instances it may be found desirable to apply a batt of fibers to both surfaces of the base fabric. When this is desired, a batt of fibers is first applied to one surface and the resulting product is then inverted and a second batt is applied to and needled to the opposite face of the base fabric in the same manner as explained above.

Referring now to FIGS. 4-7 inclusive, there is shown a form of barbed needle having a triangular cross-section in the barbed region thereof, with barbs extending in two different directions from the axis of the needle. The general form of the needle is shown in elevation in FIG. 5. This is a conventional form which may also be employed in connection with the above described, having barbs extending in only one direction from the axis thereof. Needle 15 of FIG. 5, having its upper portion of circular cross-section and bent over at 15a to facilitate its clamping in the head of a needling machine, has a barbed portion 15b of triangular cross-section. In this portion of the needle there are provided three barbs 15c extending in one direction, and three similar barbs 15d extending in another direction, which is at an angle of 120° to the direction of the barbs 15c. In the use of this type of needle in the needling machine, care is exercised to dispose the surface 15e parallel with the direction in which the warps of the base fabric extend. In this way, as best shown in FIG. 4, the two sets of barbs will point in directions at an angle of 30° to the direction in which the warps extend. As a result they will be directed at an angle of 60° to the direction in which the wefts and the batt fibers extend and at an angle of 120° in relation to each other. As indicated in FIGS. 4 and 5, the barbs 15c are preferably located at a slightly different elevation than the barbs 15d. One of these sets of barbs points in the general direction in which the material is being advanced, and the other set points toward the advancing wefts and batt fibers, not directly but at an angle of 60° thereto.

While the strength of the fabric in the machine direction is not maintained as effectively in the use of needles having barbs extending in two directions, as is accomplished with barbs extending in only one direction parallel with the warp direction, the overall strength of the fabric is nevertheless maintained at a high value. The disposition of the barbs at an angle of not more than 30° to the warps prevents any serious damage to the warps even if the barbs are brought into cutting relation with a portion of the warp yarns. It has been found that with this angular relationship, either the needles or the warp threads may be deflected sufficiently by the co-action of the tapered, pointed ends of the needles with the side

surfaces of the warps to prevent serious cutting of the warps by the barbs.

FIGS. 8 and 9 illustrate a modified form of the barbed portion of the needle. These views may be considered as taken along the lines 6-6 and 7-7, respectively, of FIG. 5, with the barb portion 15b of the needle being circular in cross-section. In this modified form of needle there will be provided a plurality of barbs 16a pointing in one direction, which will be disposed at 35° or less to the warp direction of the base fabric, and another series of barbs 16b pointed in a different direction, but not more than 35° to the direction of the warps of the base fabric. Thus, one set of barbs may be pointed at such an angle to the direction in which the fabric is being advanced, and the other set of barbs may be pointed in a corresponding direction against that in which the fabric is being advanced.

As has been indicated, the barbed portion of a needle in accordance with the invention may have a variety of different cross-sections in lieu of the triangular and circular forms illustrated. The needle may have a barbed portion of oval cross-section, diamond-shaped cross-section, or a variety of other polygonal cross-sections. However, whatever the cross-section may be, it is important that all of the barbs extend in such directions that when the needle is clamped in the head of the needling machine, none will be disposed at an angle of more than 35° and preferably not more than 30° to the warp direction. As typical of other configurations of the barbed portion of the needle, reference may be made to FIGS. 10 and 11. Thus, FIG. 10 shows a needle having an oval cross-section in the barbed region, with barbs 16c pointing toward the advancing wefts and barbs 16d pointing away from the advancing wefts, at an angle of 90° thereto. In this case the barbs are pointed at angles that are 180° apart in relation to each other. FIG. 11 shows a needle having a diamond-shaped cross-section in the barbed region, with barbs 16e and 16f pointing in the directions explained for barbs 16c and 16d, respectively. Whenever the barbs on a needle are arranged to point in different directions from the axis of the needle, it will normally be necessary or desirable to have them pointed in opposite directions in relation to the direction of advance of the fabric and batt through the needling machine. By "opposite directions" it is simply meant that some are pointed in the direction of advance of the material while others are pointed against the direction of advance of the material, with the barbs pointing in the two directions being disposed at not more than 35° to the warps of the base fabric and to the direction of advance of the base fabric and batt.

To bring about the orientation of the batt fibers in a direction substantially transverse to the length of the batt being formed, a combination of machines may be employed. As shown in FIG. 12, the original fibrous material, with no particular orientation may first be fed to a carding machine 18, which through its action serves to orient the fibers to a high degree in the direction in which the fibrous material is being advanced. This orientation of the fibers is schematically shown in FIG. 12 by the lines designated 19. After suitable orientation of the fibers in this manner, a quite thin film of the same will be carried by a conveyor 20 through a lapping machine 21. The latter may be of a well-known conventional construction. It serves to pick up sections of the thin layered carded fibers and deposit such sections on layers previously positioned crosswise of a conveyor belt 22. The latter is continuously advanced in the direction indicated by the arrow in FIG. 12, at such a rate that when the desired number of layers have been built up on conveyor 22 the latter will have advanced a distance equal to the width of the single layers being delivered by the conveyor 20. Thus, if it is desired to form a batt having ten layers of the type delivered from the carding machine, the conveyor 22 should be advanced at a rate equal

to the width of a single layer on conveyor 20 during precisely the time that the ten layers are built up on conveyor 22. Since the latter is being continuously advanced, it will be apparent that the fibers of the several layers being built up to form the batt will assume a slightly diagonal position in relation to each other. This results in disposing the oriented fibers, that extend longitudinally of the single layer on conveyor 20, in directions substantially transverse to the multi-layered batt formed on the conveyor 22. They will, however, be oriented at a small angle to the true transverse direction of the batt, as is indicated schematically by the lines 23. This, as stated, is due to the fact that the conveyor 22 is being continuously advanced as the multiple layers are being built up thereon.

The multi-layered batt formed on conveyor 22 may be delivered directly to a needling machine for application to the upper surface of the base fabric in the manner explained above. However, this is not essential and the two operations may be separately performed, if desired.

FIG. 13 schematically shows how the base fabric and the batt fibers are supplied and advanced through the needling machine. The multi-layered batt 23 may be delivered, either directly from the lapping machine or from a roll, to a conveyor belt 24 and advanced downwardly with the upper run of this belt. The latter passes around a pair of rollers 25 and 26, one of which may be driven by any suitable connections from a drive shaft connected with the needling machine. From the lower end of the downwardly moving run of the belt 24, the batt will be delivered to the upper surface of the base fabric 27, which may suitably have its free ends clipped together into endless belt form. It is supported by rollers 28 and 29, and a number of intermediate rollers if desired. One of the rollers 28 and 29 may be connected with the drive shaft of the needling machine to bring about continuous advance of the fabric in the direction indicated by the arrow. The rate of advance will correspond to the rate at which the batt is delivered to the fabric. As the latter is advanced it is carried through the needling zone of the machine. This is schematically shown as including a plurality of rows of needles 31, 13 such rows being shown, each row extending across the width of the base fabric. Needles 31 are mounted in a head 30 and are clamped in position by means of a plate 32 that may be secured by screws or bolts 33 to the top of the head. The latter is reciprocated in a vertical direction by connections from the drive shaft of the machine, a part of such connections being schematically indicated at 34. In the region in which the needles act upon the batt and the base fabric, the latter may be supported by a plate 35, or the like, having suitable openings or passages 35a therethrough, to permit the downward movement of the needles 31 into a position in which the lower ends thereof are below the upper run of the fabric 27.

After the entire outer surface of the base fabric has been covered by a corresponding length of the batt, the latter may be severed by suitable cutting blades, and the supply of the batt material may be discontinued. As has been explained, the base fabric and the batt may be cycled a number of times through the needling zone of the machine to insure effective needling of the batt fibers to the base fabric.

While various embodiments of the invention have been described in some detail, it will be understood that modifi-

cations of the same, other than those specifically referred to above, may be made within the scope of the invention as defined by the appending claims.

What is claimed is:

- 5 1. A method of producing a paper machine felt which comprises: forming a base fabric with certain yarns extending in the machine direction and other yarns extending in the cross machine direction of the felt, applying to one surface of said fabric a batt of fibers having the majority of the fibers thereof oriented in substantially the cross machine direction, and needling said batt to said base fabric by needles having all of their fiber engaging barbs disposed at an angle of not more than about 30° to the machine direction yarns.
- 10 2. A method of producing a paper machine felt which comprises: forming a base fabric with certain yarns extending in the machine direction and other yarns extending in the cross machine direction of the felt, applying to one surface of said fabric a batt of fibers having a majority 15 of the fibers thereof oriented in substantially the cross machine direction, and needling said batt to said base fabric by needles having all of their fiber engaging barbs disposed substantially parallel with the machine direction yarns.
- 20 3. A method according to claim 1 in which said needles are formed with barbs extending in only one direction from the axis of the needles, said needles being so disposed in the course of the needling operation as to have their barbs extend in a direction substantially at right 25 angles to the direction of orientation of the majority of batt fibers.
- 30 4. A method according to claim 3 in which the base fabric and batt are advanced in the machine direction as the fibers of said batt are being needled to said base 35 fabric, the barbs of said needles being pointed in a direction opposite to that in which the fabric and batt are being advanced.
- 40 5. A method according to claim 1 in which each of said needles is provided with barbs extending therefrom in directions disposed at an angle between about 120° and 180° in relation to each other, said needles being so disposed in the course of the needling operation that all 45 of their barbs extend in a direction of at least about 60° to the direction of orientation of the batt fibers.
6. A method of producing a paper machine felt as set forth in claim 1 in which at least 70% of the fibers of the batt are oriented in substantially the cross machine direction as they are needled to the base fabric.
- 50 7. A method of producing a paper machine felt as set forth in claim 1 in which said base fabric is woven and is advanced in the machine direction of the felt as the batt is applied and needled thereto.
